Primary Examiner — T Chase Nelson*Assistant Examiner* — Jonathan J. Han(74) Attorney, Agent, or Firm — Banner & Witcoff, Ltd.(57) CLAIM

The ornamental design for a shoe, as shown and described.

DESCRIPTION

FIG. 1 is a rear perspective view of a shoe showing our new design;

FIG. 2 is a rear view thereof; and,

FIG. 3 is an opposite side rear perspective view thereof.

The broken line immediately adjacent to the bottom of the shaded area defines the lower bounds of the claimed design and forms no part thereof. The broken lines showing of the race-track shaped elements and the unshaded regions therein form no part of the claimed design. The other broken lines within the shaded area represent features that form no part of the claimed design. The broken lines depicting the remainder of the shoe form no part of the claimed design.
